SWITCH

Lawrence E. Fisher and William H. Frank,
Detroit, Mich.

Application January 13, 1936, Serial No. 58,870

5 Claims. (Cl. 200—116)

This application discloses a novel circuit protective switch shown in the appended drawing whose—

Fig. 1 is a side view;

5 Fig. 2 is a section view on line 2—2, Fig. 1; and whose

Fig. 3 is an end view.

In Figs. 1—3 there is disclosed a switch wherein stationary contacts 54 are adapted to be connected through movable contacts 55 engaged by springs 56, and a U-shaped bimetallic thermal element 57 on the outside of the movable housing 58 and mounted thereon by means of pins 59 which also mount the movable contacts 55 and electrically connect these to the ends of the U-shaped thermal element 57. The bight 61 of the thermal element is bent to form a lug which is normally positioned under a catch 62 formed on an insulation block 63 secured to the base 64 in an appropriate manner. The slide 65 of the block 58 between the stationary contacts 54 is continued to form an extension 66 which passes through a slot 67 of the base 64 to be engaged by a coiled compression spring 68 housed in a base portion 69.

25 The operation of the parts is as follows: When the switch is in ON position, as on normal load, the thermal element has its lug 61 caught under the catch 62 and the housing 58 is held down in the position illustrated and the circuit is established from one contact 54 through a movable contact 55, a pin 59, and the U-shaped element 57 back through a second pin 59, a second contact 55, to the second stationary contact 54. When an overload arises, the thermal element 30 warps to the left, Fig. 1, so that its lug is free of the catch 62, whereupon the spring 68 under stress expands and causes the block 58 to move up so that its contacts 55 leave the stationary contacts 54 and open the circuit, movement of 35 the block being arrested by the engagement of the lower end of the slide against the under surface of the base 64.

We claim:

1. A circuit interrupter comprising a pair of 45 stationary contacts, a movable insulation block having cells closely fitting around and constantly closed by said stationary contacts in all positions of the block, a contact forming a wall portion of each cell and carried by the block and movable therewith to engage or be free of a stationary 50 contact in the corresponding cell, the block contacts being electrically connected by movable circuit current responsive means whereby the block contacts and such means bridge the stationary 55 contacts, the circuit current responsive means comprising the movable part of a release latch which normally holds the block in closed circuit position, and means constantly tending to move the block to open circuit position and inhibited by the latch.

2. A circuit interrupter comprising a pair of stationary contacts, a movable insulation block having cells closely fitting around and constantly closed by said stationary contacts in all positions of the block, a contact forming a wall portion of each cell and carried by the block and movable therewith to engage or be free of a stationary 5 contact in the corresponding cell, the block contacts being electrically connected, whereby they bridge the stationary contacts, the connection including a circuit current responsive release means operating on a circuit abnormality to move the block to open circuit position.

3. A circuit interrupter comprising a pair of stationary contacts, a movable insulation block having cells closely fitting around and constantly closed by said stationary contacts in all positions of the block, a contact forming a wall portion of each cell and carried by the block and movable therewith to engage or be free of a stationary 15 contact in the corresponding cell, the block contacts being electrically connected, whereby they bridge the stationary contacts, the connection including a movable circuit current responsive release latch which normally holds the block in 20 closed circuit position, and means constantly tending to move the block into open circuit position and inhibited by the latch.

4. A circuit interrupter comprising a pair of stationary contacts, a movable insulation block 30 having cells closely fitting around and constantly closed by said stationary contacts in all positions of the block, a contact forming a wall portion of each cell and carried by the block and movable therewith to engage or be free of a stationary 35 contact in the corresponding cell, the block contacts being electrically connected by circuit current responsive means whereby the block contacts and the means bridge the stationary contacts, the means also serving to control the position of 40 the block with respect to the stationary contacts and thus controlling the flow of current through the interrupter.

5. A circuit interrupter comprising a pair of stationary contacts, a movable insulation block 45 having cells closely fitting around and constantly closed by said stationary contacts in all positions of the block, a contact forming a wall portion of each cell and carried by the block and movable therewith to engage or be free of a stationary 50 contact in the corresponding cell, the block contacts being electrically connected by circuit current responsive latching means whereby the block contacts and the means bridge the stationary contacts, the latch normally holding the block in 55 circuit closing position, but operating, on overload, to permit the block to be moved away from circuit closing position automatically.
